INK FEED CONTROL MEANS FOR PRINTING PRESSES

Carl L. Erickson, Eltingville, and Walter O. Morrison, Elmhurst, N. Y., assignors to Russell Supply Co. Inc., New York, N. Y., a corporation of New York

Application February 5, 1931. Serial No. 513,564

5 Claims. (Cl. 101—357)

This invention relates to the ink feed control of printing presses of the type wherein, during printing operations, a type bed carrying the type forms is reciprocated beneath an impression cylinder, the cylinder, being depressed for a printing impression upon movement of the type bed in one direction and elevated away from the bed upon movement of the latter in a reverse direction. Such presses have a series of inking rolls for conveying ink from a fountain and applying it properly distributed to the forms upon the type bed as the bed is reciprocated. There is also a tripping means which is operable to prevent up and down movement of the impression cylinder during non-printing operation of the press and cause the cylinder to be held elevated away from the type forms as the type bed is reciprocated.

Important objects of the invention are to provide improved control means to automatically trip the ink-feeding means or cut it out of operation when the impression cylinder is tripped or held elevated and thereby prevent an objectionable accumulation of ink upon the type forms during non-printing operation of the press; to provide such an ink feed control means designed to be readily applied to a standard form of printing press; to provide such a control means in the form of an extremely simple and inexpensive device; and to provide such a device designed for installation upon a standard form of press without structural changes in the press and designed for satisfactory cooperation with the standard parts of the press.

In the drawings, Fig. 1 is a side view of a printing press partly broken away, equipped with our improved device for tripping the ink feed;

Fig. 2, a side view of the ink feed tripping device detached from the press;

Fig. 3, an edge view of the device;

Fig. 4, a perspective view of part of the mechanism of the printing press with the ink feed tripping device operatively attached thereto;

Fig. 5, a side view partly in section showing the operation of the device to permit operation of the ink-feeding means of the press;

Fig. 6, a side view, upon a larger scale than Fig. 5, showing the operation of the cam of the device to permit feeding operation of ink feed pawl;

Fig. 7, a view similar to Fig. 6 showing the cam positioned to prevent engagement of the feed pawl with the ratchet wheel; and

Fig. 8, a plan view of the ratchet feed mech-

anism, cam and associated parts upon the fountain roll shaft.

The ink feed tripping device is shown as applied to a standard form of Kelly press for which it is particularly designed. Such a press has a main frame 1 supporting a rotatable impression cylinder 2, and a type bed 3 mounted to reciprocate beneath the impression cylinder and carrying the type forms. The impression cylinder is rotated and the type bed is reciprocated by power driven means which form no part of the present invention and have been omitted from the drawings in order to simplify the showing. Upon movement of the type bed in one direction the impression cylinder, bearing the paper, is depressed toward the type forms for a printing impression, and upon movement of the type bed in a reverse direction the cylinder is elevated away from the type forms. Near one end of the frame is a trough-like ink fountain 4 one side of which is formed by a fountain roll 5. The latter is rotated step by step by means to be described hereinafter. Between the roll 5 and the impression cylinder is mounted a group of ink-distributing rolls 6 the lowermost ones of which are in position to roll upon the type forms. Certain of the other rolls of the group are vibrator rolls which are reciprocated endwise. Between the group of distributing rolls and the fountain roll 5 is a ductor roll 7 supported by rocker arms 8 to swing back and forth between the fountain roll and one of the distributing rolls to convey ink to the latter.

For the vertical reciprocation of the impression cylinder 2 the shaft 9 of the cylinder is mounted in bearings 10 which are vertically slideable in fixed frames 11 at opposite sides of the press. A yoke-like frame 12 surrounds each bearing and is mounted to shift vertically with it. A compression spring 13 interposed between each fixed frame 11 and the bearing therein tends to elevate the bearing and the shiftable frame and lift the impression cylinder away from the type forms. For depressing the impression cylinder there is a power driven mechanism including a transverse rock shaft 14 and a pair of toggles 15 interposed between the lower end of each fixed frame 11 and associated shiftable frame 12 and adapted to depress the shiftable frame when straightened. Shaft 14 has a pair of crank arms 16 fixed to it and operatively connected to the joints of the toggles by operating links or rods 17.

Power for rocking shaft 14 is transmitted from a drive shaft 18 having a pulley 19. A pinion

20 fixed to shaft 18 meshes with a gear 21 fixed upon a shaft 22 also having a fixed pinion 23. The latter meshes with a gear 24 fixed to a shaft 25, and gear 24 meshes with a gear 26 fixed to a shaft 27. A cam disk 28 is fixed to main crank 5 shaft 27 and has the impression cam groove 29 in one face. A pivoted rock arm 30 has a roller 31 at one end engaging in said cam groove, and a link or rod 32 operatively connects an intermediate point of the rock arm with a crank arm 33 fixed to rock shaft 14 and extending in an opposite direction from the crank arms 16 upon the rock shaft. Thereby when the roller 31 is in a low part of the cam groove the crank arms 16 are positioned to break the toggles and the springs 13 are free to elevate the impression cylinder. When the roller 31 is in a high point of the cam groove the shaft 14 is rocked and the crank arms 16 are swung to straighten the toggles. This causes the shiftable frames 12 to pull the bearings 10 and the impression cylinder downward against the resistance of the springs 13 for a printing impression. The reciprocation of the type bed is properly coordinated with the raising and lowering of the impression cylinder by means not shown.

There is also a tripping mechanism for disabling the operative connection between the rod 32 and the crank arm 33. This operative connection comprises a downwardly opening hook upon the rod 34, and a pin 35 upon the crank arm engaged by the hook. The latter has a straight tail portion 36 whose under side is engageable by a roller carried by a bell crank 37. Below said bell crank, near the floor, is a depressible pedal 38 which is operatively connected to the bell crank by a link or rod 39. Thereby when the pedal is depressed the bell crank will be rocked to elevate the roller and shift the hook 34 free of the pin 35. A latch device 40 releasably holds the pedal depressed. The rock shaft 14 then remains idle; the toggles 15 remain broken and the impression cylinder is held elevated by the springs 13. A spring 41 tends to elevate the pedal and rock the bell crank back to permit reengagement of the hook with the pin.

For step-by-step ink-feeding rotation of the fountain roll 5 there is a ratchet wheel 42 fixed to the shaft 43 of the roll. Pivoted upon said shaft outward of the ratchet wheel is a bell crank 44 to one arm of which is pivoted a feed pawl 45 for engaging the ratchet wheel. Said bell crank is rocked by a mechanism including a shaft 46 having a bevel gear 47 fixed to it and meshing with bevel gear 48 fixed to the power driven shaft 25. A cam 49 is fixed to shaft 38 and is adapted to operatively engage a roller borne by a crank arm 50 fixed to a short shaft 51. Also fixed to shaft 51 is a crank arm 52. A link 53 operatively connects crank arm 52 with the bell crank 44 bearing the feed pawl 45.

The ductor roll 7 is also rocked by an operative connection with shaft 46. The arms 8 supporting the ductor roll are fixed to a shaft 54 supported by bearings in the press frame, and fixed to one end of said shaft is a crank arm 55. The latter is operatively connected by a link or rod 56 with a crank arm 57 which is fixed to a short shaft 58 adjacent the shaft 51 and supported by a bearing in the side of the press frame. A crank arm 59 is fixed to the inner end of shaft 58 and has a roller in engagement with a cam 60 fixed to shaft 46. Thereby, rotation of shaft 46 causes the ductor roll to be shifted and also, through the connection previously described,

causes operation of the feed pawl. The shaft extends beyond the cam 49 and has a driving connection, indicated at 61, with a vertical shaft 62 which operates the paper feed mechanism of the press. The cams 49 and 60 upon the shaft effect the shifting of the ink feed pawl and the ductor roll in one direction and two springs 63 and 64 effect the shifting of said parts in the opposite direction. Spring 63 is connected to crank arm 52 and spring 64 is connected to crank arm 57. Both springs extend upward and are anchored to part of the improved automatic ink feed control means, as will be described hereinafter.

Our improved ink-feed control means is an extremely simple device comprising a lever 65, a pivot stud 66 for the lever, a link 67 operatively connected to one end of the lever, and a cam 68 operatively connected to the opposite end of the lever. The pivot stud has an enlarged medial portion with a reduced threaded shank 69 at one end for screwing into the ink fountain frame, and a longer reduced, threaded shank 70 at its opposite end. At the root of shank 70 is a slightly enlarged journal portion 71 affording a pivot or fulcrum for lever 65. At an intermediate point, nearer one end, the lever has an aperture to receive the journal 71, and a nut 72 is screwed upon the shank 70 to hold the lever in place. The long arm of the lever has an elongated slot 73 at its outer end and the short arm of the lever has a slot 74 at its outer end. A headed screw 75 operatively connects one end of link 67 to the lever. Said screw has a shouldered journal portion engaged in the lever slot 74 and is screwed into the link. At its opposite end the link has an elongated slot 76. The cam 68 is of segmental or sector form and has a pivot aperture 77 substantially at its center. At one side of said aperture a rivet 78 operatively connects the lever to the cam. Said rivet has a shouldered journal portion engaged in the lever slot 73. At the opposite side of its pivot aperture the cam is formed at its edge with a high arcuate portion 79 concentric with the pivot aperture and of material length. A sloping edge portion 80 of the cam merges said high portion with a low edge portion 81. The latter is also arcuate and concentric with the pivot aperture.

A press of the present type is provided with a crank handle 82 removably mounted upon the shank 43 of the fountain roll, outward of bell crank 44, and free for rotation and limited axial shifting upon the shaft. At its inner side said crank has a recess engageable with a tooth upon a collar 83 fixed upon the shaft, between the crank and the bell crank. By shifting the crank inward to engage said tooth the fountain roll may be manually rotated. Such a press is ordinarily provided with a threaded stud, not shown, which serves as a joint anchorage for springs 63 and 64 which help to operate the feed roll and ductor roll respectively. Said stud is replaced by the stud 66 of our ink feed control device.

For the installation of our automatic ink feed control device the fountain roll operating handle 82, the collar 83 and the bell crank 44 are removed from the fountain roll shaft; the cam 68 is mounted upon the shaft to rock alongside the ratchet wheel, and the bell crank, collar and handle are replaced. Also, the stud ordinarily serving as an anchorage for springs 63 and 64 is removed and the stud 66 is screwed into its place. The lever 65 is then mounted upon stud 66, the nut 72 is applied, and the springs 63 and 64 are

anchored to the projecting threaded shank of the stud. Finally, the slotted end of the link 67 is mounted upon the projecting shank of the pivot 84 connecting the adjacent crank arm 16 and 5 rod 17 of the impression cylinder depressing mechanism, and held in place by a nut 85.

Normally, when the press is idle, with the impression cylinder elevated, the cam 68 is positioned with its high portion beneath the ink feed 10 pawl 45, and the pawl is held out of engagement with the ratchet wheel 42. When the press is operated for printing, the rock shaft 14 is rocked by the cam 28 and its connections; the toggles 15 are straightened to depress the impression 15 cylinder, and the cam 68 is rocked by its link and lever connections with the rock shaft 14. Simultaneously with the rocking of the cam 68 the bell crank 44 bearing the feed pawl is rocked in a reverse direction so that the pawl is freed 20 from the high portion of the cam and engages the ratchet wheel, as shown in Figs. 5 and 6 to rotate the fountain roll 5 for ink feeding. The rocking of the bell crank 44 is effected by the rotating shaft 46 acting through the cam 49 and 25 its crank and link connections with the bell crank.

The rotating shaft 46, through its cam 60 and its operative connection with the ductor roll 7, also rocks the latter against the fountain roll to receive ink. When the high points of cams 30 49 and 60 are past the rollers upon the arms 50 and 59 the springs 63 and 64 cause the retraction of the ink feed pawl and the swinging of the ductor roll into contact with one of the ink-distributing rolls 6. Also, when the high portion 35 of the impression cylinder operating cam 28 has moved past the roller 31 of the rocking arm 30 the shaft 14 is rocked back to break the toggles 15 and permit the springs 13 to elevate the impression cylinder. This rocking of shaft 14 operates the link 67 and lever 65 to rock the cam 68 and position its high portion again beneath the ink feed pawl. Thus upon each printing operation of the press the cam 68 is operated directly 40 from the impression cylinder shifting mechanism to free the cam from the pawl and permit feeding operation thereof.

For varying the feed stroke of the ink feed pawl the press has an adjusting means including a disk 86 rotatably mounted upon the fountain roll shaft back of the ratchet wheel 42 and having an arcuate shield 87 which is shiftable beneath the feed pawl by rotation of the disk to elevate the pawl from the ratchet wheel. For 50 rotating the pawl there is a shaft 88 extending alongside the ink fountain roll and bearing a pinion 89 which meshes with teeth formed upon the disk 86. Shaft 87 is turned and adjusted by means, not shown, at its opposite end. The cam 68 does not interfere with the operation of the feed stroke adjusting means.

When the pedal 38 is depressed and latched during the operation of the press the connection 34 between the operating rod 32 and the rock shaft 14 is broken so that the shaft is rendered 55 idle and the impression cylinder remains held, or tripped in elevated position by the springs 13, for non-printing. The springs 13 break the toggles 15 and hold the idle shaft 14 with the crank arm 16 to which the ink feed control link 67 is connected, in an upright position. Said link 67 and lever 65 of our control device are then 60 rendered stationary to hold the cam 68 in such a position that its high portion remains under the ink feed pawl 45 during the full stroke of the latter and the pawl is held out of contact with

the ratchet wheel, as shown in Fig. 7. Thereby, when the pedal 38 is depressed to trip the impression cylinder the ink-feeding rotation of the pawl is automatically stopped. This positively prevents an objectionable accumulation of ink upon the type forms during non-printing operation of the press. The automatic operation of the control device renders it independent of the operator who might neglect to cut off the ink feed.

Presses of the type shown and described have heretofore been provided with an ink feed cut-off which is operated in conjunction with a paper feed mechanism. When the press is adjusted to cut out the paper feed mechanism, however, for hand feeding of the press, said ink-feed cut-off becomes inoperative. Consequently upon an interruption in the press feed, ink accumulates upon the type forms. Our simple control device operates independently of the paper feed. It is designed for proper cooperation with the standard press mechanism and for ready installation upon the press without structural alterations in the latter except the replacement of collar 83, as supplied originally, with a similar one narrow enough to make room for cam 68.

What we claim is:

1. In a printing press having a reciprocable type bed and an impression cylinder shiftable toward and from the type bed for printing, a power operated rock shaft; an operative connection between said rock shaft and the impression cylinder for shifting the latter toward the type bed for printing impressions; means operable to prevent operation of said rock shaft and consequent shifting of the impression cylinder; an ink-feeding mechanism including a fountain roll, a ratchet wheel, and a pawl to rotate the ratchet wheel and fountain roll; and a controlling mechanism for said ink-feeding mechanism comprising a lever pivoted at a medial point, a link operatively connected to the rock shaft and to one end of the lever and a pivoted cam operatively connected to the opposite end of the lever and engageable with the pawl to shift it free of the ratchet wheel, the cam being held by the rock shaft through said link and lever to hold the pawl disengaged from the ratchet wheel when the rock shaft is idle and the impression cylinder is away from the type bed and being rockable by the rock shaft through said link and lever to permit engagement of the pawl with the ratchet wheel for ink feeding when the shaft is rocked.

2. A device for controlling the ink feed of a printing press comprising a lever designed for pivotal connection at a point intermediate its ends to the press; a link operatively connected at one end to one end of said lever and formed at its opposite end for operative connection to the impression cylinder depressing mechanism of the press, and a cam formed for pivotal mounting upon the fountain roll shaft of the press, operatively connected to the opposite end of the lever to be rocked thereby, and formed to engage the feed pawl of the fountain roll and shift it to an inoperative position.

3. In a printing press having a reciprocable type bed and an impression cylinder shiftable toward and from the type bed for printing, a power operated rock shaft; a crank arm fixed to said rock shaft; a link pivotally connected at one end to said crank arm; an operative connection between the opposite end of said link and the impression cylinder including toggle links for shifting the cylinder toward the type bed for printing impressions; an ink-feeding mechanism
